UNITED STATES PATENT OFFICE.

JACOB M. SCHNEBLY AND JAMES C. BEARD, OF KAHOKA, MISSOURI.

COLLAPSIBLE POULTRY-COOP.

1,050,855.

Specification of Letters Patent. Patented Jan. 21, 1913.

Application filed February 3, 1912. Serial No. 675,256.

To all whom it may concern:

Be it known that we, JACOB M. SCHNEBLY and JAMES C. BEARD, citizens of the United States, residing at Kahoka, in the county of Clark and State of Missouri, have invented 5 certain new and useful Improvements in Collapsible Poultry-Coops, of which the following is a specification, reference being had to the accompanying drawings.

10 Our invention relates to new and useful improvements in the art known as care of live stock and more particularly to a poultry coop, and our object is to provide a device of this character which is collapsible, 15 whereby the same may be compactly folded for shipment and readily cleaned when desired.

A further object of the invention resides 20 in providing a device provided with beaded slip joints, whereby the walls thereof may be interlocked, and a still further object resides in providing a device having vertically 25 movable end walls and a longitudinally slid- able bottom thereon.

25 Another object of the invention resides in providing means on the lower edges of the side and end walls of the device for slidably retaining the bottom to the device, and still another object resides in providing a device 30 which is extremely simple and durable in construction, inexpensive to manufacture, and one which will be very efficient and useful in operation.

With these and other objects in view, our 35 invention consists in the novel features of construction, combination and arrangement of parts as will be hereinafter referred to and more particularly pointed out in the specification and claims.

40 In the accompanying drawings forming a part of this application, Figure 1 is a perspective view of the device set up. Fig. 2 is a horizontal section therethrough. Fig. 3 is a vertical transverse section through the 45 device. Fig. 4 is a vertical longitudinal section, and, Fig. 5 is a perspective view of one of the slidable caps or locking strips used for securing the upper edges of the side and top walls together.

50 In carrying out our invention, we shall refer to the drawings in which similar reference characters designate corresponding parts throughout the several views and in which—

55 1 and 2 indicate the side walls of our improved device, while 3 and 4 indicate the

upwardly converging top walls, said top and side walls being all formed of a single sheet of metal, and the side edges of the side walls and the similar edges of said top 60 walls are rolled outwardly to form the rolled beads 5 and 6, respectively. The lower edges of the side walls are also rolled inwardly to form similar beads 7, 65 said latter beads being extended just below the lower edge of the beads 5 on the side edges of said side walls.

The end walls 8 and 9 each have the side edges thereof provided with inwardly rolled beads 10 and 11, respectively, which are 70 designed to slidably receive therein, the outwardly turned beads on the side edges of the side walls 1 and 2, and the upper edges of said end walls, which are inclined coincident to the inclination of the top walls 3 75 and 4 of the device, are provided with outwardly rolled beads 12 and 13, respectively, said beads on the upper edges of the end walls being adapted to abut and aline with the beads 6 on the edges of the top walls 3 80 and 4, when said end walls are properly positioned. The end wall 8 which, for convenience, may be termed the front wall of the device, is slightly shorter than the opposed end wall, or what may be termed the 85 rear wall 9, and the lower edges of said walls 8 and 9 are provided with inwardly rolled beads 14 and 15, respectively, the bead 15 being disposed in the same horizontal plane as the beads 7 on the lower 90 edges of the side walls, while the bead 14 is disposed in a plane just above the same. A bottom 16 which is adapted to be slidably disposed in the device from the end 95 having the wall 8 thereon, is provided on its longitudinal side edges with the downwardly rolled beads 17 which are adapted to be received by the upwardly or inwardly rolled beads 7 on the lower edges of the side walls 1 and 2. The inner end edge of the bottom 16 is adapted to rest upon the bead 15 of the end wall 9, while the opposite or outer end edge of the bottom is provided with a downwardly rolled bead 18 which corresponds with the bead 15 at the 100 opposite end of the device when the bottom is properly positioned therein and forms a handle member or finger piece for said bottom, whereby the latter may be readily positioned or removed, as desired.

110 As before stated, the beads 12 and 13 at the upper edges of the walls 8 and 9, re-

spectively, are adapted to align with the beads 6 at the ends of the top walls 3 and 4, when said end walls are properly positioned, and in order to lock the upper edges of the side and top walls together, we provide the 5 ⁷⁰ ⁷⁵ ⁷⁵ ⁸⁰ ⁸⁵ ⁹⁰ ⁹⁵ ¹⁰⁰ ¹⁰⁵ ¹¹⁰ ¹¹⁵ ¹²⁰ ¹²⁵ ¹³⁰ ¹³⁵ ¹⁴⁰ ¹⁴⁵ ¹⁵⁰ ¹⁵⁵ ¹⁶⁰ ¹⁶⁵ ¹⁷⁰ ¹⁷⁵ ¹⁸⁰ ¹⁸⁵ ¹⁹⁰ ¹⁹⁵ ²⁰⁰ ²⁰⁵ ²¹⁰ ²¹⁵ ²²⁰ ²²⁵ ²³⁰ ²³⁵ ²⁴⁰ ²⁴⁵ ²⁵⁰ ²⁵⁵ ²⁶⁰ ²⁶⁵ ²⁷⁰ ²⁷⁵ ²⁸⁰ ²⁸⁵ ⁵⁶³⁰ ⁵⁶³⁵ ⁵⁶⁴⁰ ⁵⁶⁴⁵ ⁵⁶⁵⁰ ⁵⁶⁵⁵ ⁵⁶⁶⁰ ⁵⁶⁶⁵ ⁵⁶⁷⁰ ⁵⁶⁷⁵ ⁵⁶⁸⁰ ⁵⁶⁸⁵ ⁵⁶⁹⁰ ⁵⁶⁹⁵ ⁵⁷⁰⁰ ⁵⁷⁰⁵ ⁵⁷¹⁰ ⁵⁷¹⁵ ⁵⁷²⁰ ⁵⁷²⁵ ⁵⁷³⁰ ⁵⁷³⁵ ⁵⁷⁴⁰ ⁵⁷⁴⁵ ⁵⁷⁵⁰ ⁵⁷⁵⁵ ⁵⁷⁶⁰ ⁵⁷⁶⁵ ⁵⁷⁷⁰ ⁵⁷⁷⁵ ⁵⁷⁸⁰

terlocking means between the end and side walls to permit vertical movement of the former with respect to said side and top walls, means engaging the upper edges of the end walls and the ends of said top walls, to lock said end walls against vertical movement, a pair of inwardly rolled beads secured to the end wall having the opening therein, said beads being disposed vertically on opposite sides of said opening, a door for said opening provided with outwardly rolled beads slidably arranged in the beads on said end wall, the locking means for said

end walls also forming a means to prevent the entire removal of said door from the end walls, and a sliding bottom for the device movable longitudinally thereof.

In testimony whereof we hereunto affix our signatures in the presence of two witnesses.
